UNITED STATES PATENT OFFICE

2,269,016

MAGNETIC VALVE

Willis H. Gille, St. Paul, Minn., assignor to Minneapolis-Honeywell Regulator Company, Minneapolis, Minn., a corporation of Delaware

Application November 13, 1939, Serial No. 304,093

10 Claims. (Cl. 236—75)

My invention relates to improvements in automatic control and operation of electric valves and has more particularly as its object to provide means embodied in magnetic valves to prevent them from sticking in open position due to residual magnetism continuing to attract the core or armature after the valve has been deenergized.

Another object of my invention is to provide a magnetic valve having a lift winding and a drop-out winding in combination with a control arrangement whereby the drop-out coil is shunted for opening the valve.

Another object is to provide a magnetic valve having series connected lift and drop-out windings of such relative magnetic effect that the valve is opened by the lift winding whenever the drop-out winding is shunted and the valve is closed whenever the shunt is interrupted to cause current to flow in series through the coils.

Another object is to provide a magnetic valve having lift and drop-out windings connected in series and a manual opening device for power failure operation including recycling contacts for shunting the drop-out winding, the manual opening device being of a type which latches the valve in almost open position, the valve opening fully upon resumption of power, releasing the manual device and energizing the two windings in series to close the valve.

Further objects of the invention will become apparent from the following detailed description and annexed drawing.

The single figure of the drawing is a cross-sectional view of my improved valve showing diagrammatically the electrical connections for automatic control thereof.

Referring to the drawing, a valve body is designated by the reference numeral 10 and comprises an inlet connection 11 and an outlet connection 12. The valve body is provided with the usual transverse partition 13 which is apertured to provide a valve seat therein. Cooperating with said valve seat is a valve 14 which is rigidly secured to a valve stem 15 by suitable means such as by being threaded thereto. Mounted on the valve body 10 is a solenoid valve actuating mechanism.

The solenoid actuating mechanism comprises coils 16 and 35. The coil 35 is located on a flanged disc 17 of magnetic material, which disc in turn is located upon a relatively thick circular plate 18. The latter plate 18 is supported by the valve housing 10 and it is secured thereto in fluid tight relation. The coil 16 is mounted

upon a disc 34 having a flanged opening through its central portion, the disc 34 serving to space or separate the coils 16 and 35. As will be described later in the specification, the coil 16 is a lift coil for purposes of opening the valve and the coil 35 is a drop-out coil the purpose of which is to cause positive closure of the valve to insure against sticking of the valve in open position.

10 Extending within the coils is a sleeve 19 of suitable non-magnetic material such as brass. Secured within the upper end of the sleeve 19 is a sleeve 20 which is also of non-magnetic material preferably having good electrical conductivity such as copper. The sleeve 20 is secured to the sleeve 19 by any suitable means to insure a fluid tight joint. Extending through the sleeve 20 is a pin 21 which is of magnetic material. This pin terminates in a head 22 which head is provided with a conical extremity 23.

A core or plunger of magnetic material 24 is loosely mounted within the sleeve 19 and is designed to be actuated in response to energization and deenergization of the coils 16 and 35 as will be presently described. This core is connected to the valve stem 15 through a lost motion connection. This connection is formed by providing the core 24 with an elongated cylindrical passage 25 in which is slidably located a cylindrical head 26 of valve stem 15. The lower end of the passage 25 is closed by means of a plug 27. Mounted upon this plug is a spring 28, having its opposite end seated against the head 26. If the valve 14 is stuck to its seat when the solenoid 35 is energized, the spring 28 permits the core 24 to move and gain momentum so that a considerable amount of kinetic energy is available to break the valve loose when the spring is finally taken up. It should also be noted that, since the spring 28 holds the head 26 against the core 24 while the valve is open, a hammer action is obtained which insures the firm seating of the valve when it is closed.

45 The upper end of the solenoid core 24 is provided with a recess having two conical surfaces 29 and 30. The conical surface 30 is adapted to engage the conical surface 23 of pin 21 to limit the upward movement of the core. The conical surface 29 is adapted to cooperate with a similar conical surface 31 on member 20 in such a manner that the core is guided into engagement with stop 23. In order to guard against any dash-pot action a transverse passage 48 is provided in the core 24 which passage is in communication with a recess in the upper end of the

core. This is necessary because of the presence of the fluid within the space between the core and the sleeve 20. In this connection, attention is called to the fact that the core is loosely mounted within the sleeve 19 so as to permit fluid to flow around the same. This is of considerable importance inasmuch as it serves to cool the windings of the coils 16 and 35 to prevent excessive heating thereof during prolonged operation.

On top of the coil 16 there is located a disc 32 of insulating material. Secured to said disc is a flanged disc 33 of magnetic material. Also located on said insulating plate is a second plate 31 of magnetic material. A circular armature 41 is secured to a switch blade 42 which switch blade carries an electrical contact 36 adapted to cooperate with a stationary contact 43 located upon the insulating disc 32. The armature 41 serves to complete the magnetic path between magnetic members 33 and 31 upon energization of the coil 16. The plate 31 has three inwardly extending projections (not shown) adjacent which the armature 41 will be attracted most strongly. This will result in a three-point holding action between each plate and the armature which will lessen the danger of the armature being held unevenly so as to cause chattering or vibration thereof. The details of construction of the magnetic plates 33 and 31 however, do not form a part of the present invention. The details of construction of these plates are described more fully in the patent to Cyr 2,155,358.

By reason of the resilience of switch blade 42 to which the armature 41 is attached, the latter member is held in the position indicated in the drawing when the coil 16 is deenergized.

The disc 18 is provided with a cylindrical recess in the interior thereof in which is secured a resilient spring disc 44. This spring disc is secured in place by means of a plurality of rings 45. It will be noted that the inner edge of spring 44 is turned upwardly. This upwardly turned portion is designed to cooperate with a conical shoulder 46 at the lower end of the core 24.

It will be noted that two possible magnetic paths are provided for the flow of flux upon energization of the coil 16. One of these paths is through the disc 17, the casing 47 which is of magnetic material, the plate 31, the armature 41, the plate 33 and the core 24. The other of these paths is through disc 17, casing 47, plate 31, armature 41, pin 21 and the core 24. Flux flowing through the first mentioned of these two paths is not shaded while the flux flowing through the second mentioned of these two paths is shaded by reason of the effect of the non-magnetic conducting sleeve 20 which acts as a shading ring. The result is that the flux flowing through these two paths is displaced approximately 90°. This produces a much smoother action of both the core and the armature 41 and eliminates much of the vibration which is usually present if the device is operated by alternating current.

The spring disc 44 by reason of such engagement of its inner turned edge with the shoulder 46 upon energization of the coil 16 serves further to center the core within the sleeve 19 and at the same time to yieldably urge the core downwardly so that upon deenergization of the coil 16 the spring disc functions as a means for returning the core to closed position of the valve.

For a more complete description and operation of this portion of my valve reference is made to

the patent to Cyr mentioned above, the patents of Willis H. Gille No. 2,114,961 and No. 2,181,423.

Numeral 49 designates a terminal box formed as a part of the upper structure of the valve and which houses a portion of a manual operating means for the valve. The terminal box 49 is shown partly broken away. The manual operating means includes a shaft 50 journaled in a stud 51 which is threaded into the valve body 10. Connected to the shaft 50 is a cylindrical member 52 which has secured at its upper end a knurled knob 53 designed to be manually rotated by the operator. The shaft 50 and the cylindrical member 52 are secured together by means of a rivet 54, although it is to be understood that any other suitable securing means can be employed and if desired these two members can be integrally formed. The cylindrical member 52 is enlarged at its lower extremity 55. This enlarged portion 55 is provided with an opening 56 on its underside into which extends one terminal of a coil spring 57. The other end of the spring extends into an opening 58 in the upper portion of stud 51. The spring 57 is normally tensioned so as to tend to move member 52 and the attached shaft 50 upwardly and at the same time to rotate it in a clockwise direction looking downwardly. As is apparent from the drawing the shaft 50 is provided at its lower end with a conical shoulder 59 and by reason of the tendency of the spring 57 to urge shaft 50 upwardly, this conical head is yieldably urged into engagement with the edge of the opening in the underside of stud 51.

The shaft 50 has attached at its lower end an arm 61. Secured to the arm 61 is a downwardly extending pin 62. This pin 62 is adapted to cooperate with a curved surface 63 of a core actuating member 64. The core actuating member 64 is pivotally mounted on a pin 65 through a pair of ears 66 as shown. The member 64 is provided at one end with a downwardly extending portion which terminates in a fork 67, the fork straddling the valve stem and being adapted upon turning of member 64 around pivot 65 in a counter-clockwise direction to engage the lower end of the core 24. The other end of member 64 consists of a flat strip which is normally horizontally disposed and which terminates in the portion 68 normally resting against the end of shaft 50. With the parts in their normal position the arm 61 is in a position where further rotation of shaft 50 in a counter-clockwise direction causes pin 62 to ride on the curved surface 63. When it is desired to manually operate the valve, for instance when there is no electrical power available, the shaft 50 is rotated in a counter-clockwise direction by means of the knurled knob 53 so that the pin 62 is caused to engage the curved surface 63 and to tilt the member 64 about the pivot 65. This causes the core 24 to be moved upwardly and the valve to be opened. In this position the pin 62 is engaging the flat portion of strap 64, and by reason of the weight of the core 24 resting on the fork 67 the shaft 50 is held in that position against the action of spring 57, which as previously stated, tends to rotate the shaft in a clockwise direction. The tendency of the weight of the core to hold the shaft 50 in position is increased by reason of the fact that in order for the shaft to be rotated back pin 62 must travel over a circular path a portion of which is closer to pivot 65 than the position occupied by pin 62 when the valve has been manually opened. Since the pin travels through a horizontal path it is ac-

cordingly necessary for the pin to press down the left hand portion of lever 64 and accordingly raise the core still further in order to traverse this circular path. The effect is that the pin is frictionally held at the bottom of an inclined surface over which it must travel to return to the normal position.

While the rotation of shaft 50 causes the core 24 to be raised sufficiently to move the valve to open position the core is not raised as far as it is by reason of energization of coil 16. Accordingly as coil 16 is energized at the time that the shaft 50 is manually moved or if it is subsequently energized the frictional engagement of member 64 with pin 62 will not be present and consequently the spring 51 will be effective to rotate shaft 50 to a position it is in when the valve is closed in which position the member 64 in no way interferes with the normal function of the valve.

Secured to the terminal box 49 are terminals 74 and 76. Secured to the terminal 74 within the terminal box 49 is a contact carrying arm 71. Secured to the terminal 76 also within the terminal box 49 is a resilient switch blade 78 which carries contact 79 adapted to be moved into engagement with a contact 80 by the contact carrying arm 71. The blade 78 is resilient and by reason of such resiliency tends to move in a direction such as to cause engagement of contacts 79 and 80. When the valve actuating member is in its normal position this tendency of blade 78 to effect the engagement of the contacts 79 and 80 is resisted by a stud 82 secured to the member 52 and having attached thereto a circular disc 83 which bears against the switch blade 78. Upon rotation of member 52 to open the valve manually disc 83 is rotated away from the switch blade 78 permitting the same to cause engagement of contacts 79 and 80.

As pointed out above, the coil 16 serves as a lift or opening coil and the coil 35 acts as a drop out coil to insure closure of the valve when it is desired that it should close. As will be presently pointed out, when the electrical connections are traced coils 16 and 35 are normally connected in series with a source of power when the valve is in closed position. The combined resistance of the two coils is such that when they are in series there is only a very small and negligible consumption of power. The current flow when the two coils are in series is of course very low. The coil 35 however has a greater number of turns of wire than the coil 16 has and the wire of coil 35 has greater resistance than that of coil 16. Thus when the two coils are energized in series coil 35 has a greater number of ampere turns than does coil 16 and as a result the magnetic effect of coil 35 preponderates over that of coil 16. Thus whenever the valve is in a closed position the coil 35 tends to maintain it closed, the magnetic center of the core 24 being in such a position with respect to the field of coil 35 that the field of coil 35 will normally urge the core 24 downwardly. The path of flux of the coil 35 as can be seen is through the disc 17, casing 47, disc 34, and core 24.

In order to open the valve the electrical connections are changed so as to shunt the coil 35 and connect the coil 16 directly across the power source. By thus removing the resistance of coil 35 from the circuit through the coil 16 there is a considerably greater flow of current through the coil 16 so as to substantially increase its magnetic effect. While it is to be seen that there is always at least a small current flowing through

coil 16 the magnetic effect of coil 16 only becomes appreciable when the coil 35 is shunted out of the circuit and thus when I speak of energizing the coil 16 for opening the valve I refer to completion of the circuit therethrough which does not include the coil 35.

Referring to the drawing, numeral 85 designates a thermostat of conventional type having electrical connections whereby the operation of the valve is normally automatically controlled. The thermostat 85 comprises a bimetallic element 86 to which are attached contact arms 87 and 88 engageable with fixed electrical contacts 89 and 90, respectively. Blade 87 and contact 89 are less widely spaced than blade 88 and contact 90 so that upon movement of blade 87 in the direction of contact 89 engagement will be effected before the engagement of the blade 88 and contact 90. The blades 87 and 88 move towards their respective contacts in response to a drop in temperature and blade 88 engages its respective contact at a temperature which may be 1° or 2° lower for example than the temperature at which blade 88 engages contact 89.

20 A step-down transformer 92 supplies power for the operation of the valve. This transformer comprises a line voltage primary 93 and a low voltage secondary 94. The primary 93 is connected to line conductors 95 and 96.

25 The valve may be employed to regulate the flow of gas or other fuel to a fluid fuel burner to heat a room or other space. In such case the thermostat 85 is located in the space to be heated. As shown in the drawing the thermostat is in satisfied position, that is the position which it assumes when the temperature of the room is above the desired value. Under these conditions the valve is closed and the coils 16 and 35 are energized through the following circuit: from

30 secondary 94 through wire 100, wire 101, wire 102, coil 35, wire 103, wire 104, coil 16 and wire 105 back to secondary 94. Upon the temperature falling the bimetallic element 86 will cause blade 87 to move to the left into engagement with contact 89. The engagement of these elements however does not establish any circuit but if the temperature continues to fall blade 88 will engage contact 90 whereby the following circuit is completed shunting the coil 35 and connecting coil 16 directly across the source of power: from sec-

35 ondary 94 through wire 100, wire 101, wire 106, contact 89, blades 87 and 88 of thermostat 85, contact 90, wire 107, wire 108, wire 109, wire 104, coil 16 and wire 105 back to secondary 94. This circuit will, as pointed out above, increase the magnetic effect of coil 16 to such an extent that almost immediately the armature 41 will be drawn down in the direction of engagement with magnetic members 33 and 37 and causing the switch blade 42 to bring contact 36 into engagement with contact 43.

40 Upon this taking place the following holding circuit for coil 16 is established: from secondary 94 through wire 100, wire 101, wire 106, contact 89, blade 87, bimetallic element 86, wire 110, contacts 43 and 36, blade 42, wire 111, wire 109, wire 104, coil 16, and wire 105 back to secondary 94. It will be noted that this holding circuit is independent of the engagement of blade 88 and contact 90 so that if the temperature

45 should rise very slightly so as to cause disengagement of blade 88 and contact 90, the solenoid coil 16 would not be deenergized because of the continuance of the maintaining circuit. Completion of the circuits just described shunting the

coil 35 of course causes the magnetic effect of coil 35 to be terminated.

Upon the energization of coil 16, core 24 will be moved upwardly and will cause the spring 28 to be compressed between the plug 27 and the head 26 of the valve stem 15. After a short period of time, this action will raise the valve from its seat. Due to the fact that the core is allowed to travel a considerable distance before the spring 28 is compressed enough to cause movement of the valve stem, the kinetic energy of the moving core will be effective to move the valve from its seat in the event it is stuck thereto. The core 24 will continue to move upwardly until the conical surface 30 engages the head of the pin 21. In this position of the core the shoulder 46 will engage the inturned edge of spring disc 44 in such a manner that the spring 44 will exert a slight tension on the core tending to pull it away from engagement with surface 23. As long as the coil 16 is energized this tendency is resisted by the holding action of the core but as previously indicated is effective to cause downward movement of the core upon deenergization of the coil 16. As previously indicated, the flux which is effective on the core flows through two paths, one of which is shaded and the other of which is not. In this manner, a more uniform holding action is secured and chattering is avoided. When the temperature rises sufficiently so that blades 87 and 88 disengage from contacts 89 and 90, the coil 16 will be deenergized, that is, the shunt circuit around coil 35 will be interrupted and due to the combined effects of gravity, the spring disc 44 and the magnetic effect of coil 35, the core 24 and valve 14 will be moved downwardly together so as to cause the valve 14 to be firmly seated. It will be seen therefore that as soon as the shunt circuit is interrupted the two coils 16 and 35 are again energized in series. Under these conditions, as pointed out above, the magnetic effect of coil 16 is negligible, the magnetic effect of coil 35 preponderating and positively urging the core 24 downwardly to insure that the valve closes and does not stick in open position. The magnetic effect of coil 35 tends to neutralize and overbalance the slight magnetic effect of coil 16 when the coils are energized in series. It will be seen therefore that I have provided a compact coil arrangement which provides positive insurance against the valves sticking in open position and yet does not require that a pair of contacts be made to complete a circuit when it is desired that the valve be closed.

If for any reason there is a power failure as is often the case and it is desired to open the valve manually knurled knob 53 is rotated so as to cause rotation of shaft 59 and rotation of pin 62 on to the curved surface 63 on to the lever 64. As previously explained, this causes upward movement of the right-hand end of lever 64 causing the core to be moved upwardly so that the valve is opened. Due to the fact that in its valve open position pin 62 is resting on a flat portion of lever 64 and the weight of the core is resting upon the right-hand end of lever 64, the pin 62 will be held frictionally on the lever against the action of the spring 57 which tends to return the same to the normal inoperative position.

The rotation of knurled knob 53 and shaft 59 in a manner to open the valve causes the disc 83 to be rotated away from engagement with the resilient switch blade 78 so as to allow engagement of contacts 79 and 80. Engagement of these contacts results in the establishment of an

energizing circuit for coil 16 which does not extend through the coil 35, that is a shunt circuit for coil 35. This circuit is as follows: from secondary 94 through wire 100, wire 113, blade 78, contacts 79 and 80, contact arm 77, wire 114, wire 108, wire 109, wire 104, coil 16, and wire 105 back to secondary 94. Since as previously stated the valve has been opened when there is no power available, this circuit will not be effective to energize coil 16 until the power is restored. As soon as power returns however, coil 16 will be energized causing core 24 to be lifted to its uppermost position and as previously explained pin 62 will be released to permit the shaft 59 to rotate to its original position. As soon as the manual operator is thus released contacts 79 and 80 will be again separated and the circuit last described through the coil 16 will be interrupted, that is, the shunt circuit will be interrupted and the coils will again be energized in series. This will cause immediate closure of the valve in the manner previously described. In this position the parts are as shown in the drawing and the manual operator is in no way interfering with the control of the coils. If at the time the power is restored the temperature is such that blades 87 and 88 are in engagement with contacts 89 and 90, coil 16 will remain energized through the circuits already described and the valve will remain open. Thus it will be seen that no matter what position the thermostat is in when power returns, if the valve has been manually opened the parts will immediately return to position for automatic control.

From the foregoing it will be apparent to those skilled in the art that I have provided a novel improvement in the operation and control of magnetic valves whereby the difficulty of such valves sticking in open position is positively eliminated. The additional coil is very compact and the manner of its control is such that a preferred type of thermostat may be used and the use of additional switching or other equipment is made unnecessary.

While I have shown a specific embodiment of my invention it will be understood that this is for purposes of illustration only and that my invention is to be limited only by the scope of the appended claims.

50 I claim as my invention:

1. In a magnetically operated valve, in combination, a pull in coil and a drop out coil connected in series, control means comprising electrical connections for shunting the drop out coil to increase the energization of the pull in coil for opening the valve, said coils having such relative magnetic effect that when connected in series the drop out coil operates the valve to closed position, said control means including a thermostat having contacts which close at a predetermined temperature whereby a circuit is produced through said electrical connections shunting said drop out coil, and manually operable means for releasably latching said valve in a position near full open when power fails, said last means including contacts which are closed and which complete a shunt circuit around said drop out coil when said valve is latched in said position, whereby when power is resumed said pull in coil is energized opening said valve wide open, said manually operable means releasing whereby said shunt circuit is interrupted causing closure of the valve.

2. In a magnetically operated device, in combination, an armature operatively connected to

said device, a pair of coils having unequal and opposing magnetic fields for operating said armature, a source of energy, means connecting said coils in series to said source so that the coil having the stronger field determines the armature position, means responsive to a condition indicative of the need for operation of said device, a pair of switches sequentially closable by said condition responsive means upon a unidirectional change in said condition, a first circuit for shunting said stronger coil so that the coil having the weaker field determines the armature position, said first circuit including both said switches in series, a third switch operable upon increased energization of said weaker coil due to shunting of said stronger coil, and a second circuit for shunting said stronger coil including the first of said pair of switches to close and said third switch in series.

3. In a magnetically operated device, in combination, an armature operatively connected to said device, a pair of coils having unequal and opposing magnetic fields for operating said armature, a source of energy, means connecting said coils in series to said source so that the coil having the stronger field determines the armature position, means responsive to a condition indicative of the need for operation of said device, a pair of switches sequentially closable by said condition responsive means upon a unidirectional change in said condition, a first circuit for shunting said stronger coil so that the coil having the weaker field determines the armature position, said first circuit including both said switches in series, a third switch operable upon increased energization of said weaker coil due to shunting of said stronger coil, a second circuit for shunting said stronger coil including the first to close of said pair of switches and said third switch in series, a fourth switch, means manually operable to close said switch and simultaneously move said armature to an intermediate position when said coils are deenergized, latch means for holding said switch in closed position, connections between said armature and said latch means for tripping said latch means when said armature is moved to said second position, and a third circuit for shunting said stronger coil including said fourth switch.

4. A thermostatically controlled valve, comprising in combination, an armature operatively connected to said valve, a pair of coils having unequal and opposing magnetic fields for operating said armature, means connecting said coils in series so that the coil having the stronger field holds the armature in a position such as to maintain the valve closed, means responsive to a condition indicative of the need for operation of said valve, a pair of switches sequentially closable by said condition responsive means upon unidirectional change in said condition, a first connection for short-circuiting said stronger coil so that the coil having the weaker field becomes effective to move the valve toward open position, said first connection including both said switches in series, a third switch closable in response to increased energization of said weaker coil due to short-circuiting of said stronger coil, and a second connection for short-circuiting said stronger coil including the first to close of said pair of switches and said third switch in series.

5. In a device magnetically operable between a first safe position and a second active position, in combination, an armature operatively connected to said device, a pair of coils for operat-

ing said armature, stop means of magnetic material for engaging said armature when said device is moved to its active position, one of said coils having a greater number of turns than the other and positioned with respect to said armature so as to operate it in the direction of said safe position, said other coil being positioned so as to operate said armature in the direction of said active position, a source of energy, a single circuit for causing operation of said device to safe position, said circuit connecting said coils in series to said source so that said one coil controls the armature, a circuit for causing operation of said device to active position including a connection for shunting said one coil so that said other coil controls the armature, and switch means in said connection for selectively controlling the flow of current in said circuits.

6. In combination, a valve mounted for movement in a substantially vertical direction, a stem attached to said valve for operating it between an upward open position and a downward closed position, an armature mechanically connected to said stem, and operable between an upward position corresponding to open position of said valve and a downward position corresponding to closed position of said valve, a pair of coils for operating said armature, one of said coils having a greater number of turns than the other and positioned with respect to said armature so as to operate it in valve closing direction, said other coil being positioned so as to operate said armature in valve opening direction, stop means of magnetic material for limiting movement of said armature in valve opening direction, a source of energy, a single circuit connecting both said coils in series with said source so that said one coil operates said valve to closed position, and a connection including switch means for shunting said one coil so that said other coil controls the armature and thereby operates said valve to open position, said switch means being operable to open and close said connection and thereby cause closure and opening, respectively, of said valve.

7. In a valve operable between open and closed positions, in combination, an armature operatively connected to said valve, a pair of coils for operating said armature, one of said coils having a greater number of turns than the other, said one coil being positioned so as to operate said armature to close said valve, said other coil being positioned so as to operate said armature to open said valve, a source of electrical energy, a circuit connecting said coils and said source in series so that the same current flows through both coils, thereby causing said one coil to predominate over said other coil and close said valve, and a connection shunting said one coil including switch means, said connection when completed effectively deenergizing said one coil so that said other coil opens said valve, said switch means being operable by opening and closure thereof to selectively control the operation of said valve to closed and open positions, respectively.

8. In a valve operable between open and closed positions, in combination, an armature operatively connected to said valve and biased to a position in which said valve is closed, a pair of coils for operating said armature, one of said coils having a greater magnetic effect than the other, said one coil being positioned so as to operate said armature to close said valve, said other coil being positioned so as to operate said armature to open said valve, a source of electrical energy, a circuit connecting said coils and said source in

series so that the same current flows through both coils, thereby causing said one coil to predominate over said other coil and close said valve, and a connection shunting said one coil including switch means, said connection when completed effectively deenergizing said one coil so that said other coil opens said valve, said switch means being operable by opening and closure thereof to selectively control the operation of said valve to closed and open positions, respectively.

9. In a magnetically operated valve for controlling a supply of heating fluid, in combination, an armature for actuating the valve, a pull in coil and a drop out coil operatively associated with said armature and connected in series, control means comprising an electrical connection for shunting the drop out coil to increase the energization of the pull in coil for opening the valve, said coils having such relative magnetic effect that when connected in series the drop out coil 20 operates the valve to closed position, said control means including thermostatic means movable in response to a condition indicative of the necessity for supplying said heating fluid, and switch means in said connection and controlled by said thermostat so as to complete said connection when said thermostat calls for a supply 25 of fluid and to open said connection when said

thermostat calls for discontinuance of said supply.

10. In a magnetically operated valve, a first winding, a second winding, armature means associated with said windings and connected to said valve for operating said valve between open and closed positions, said armature means having its magnetic center so arranged with respect to said windings that the effect of said first winding urges said armature means in opening direction of the valve and the effect of said second winding urges said armature means in closing direction of the valve, means for energizing both windings, means for connecting said windings in series, said windings having such relative magnetic strength that the effect of said second winding preponderates when said windings are connected in series, and an electrical connection including switch means for shunting said second winding, said switch means operating when closed to complete said connection and thereby render said first winding effective to open said valve, said switch means operating when opened to break said connection, thereby connecting said windings in series and rendering said second winding effective to close said valve.

WILLIS H. GILLE.
